US0D1066363S

(12) **United States Design Patent** (10) **Patent No.:** **US D1,066,363 S**
(45) **Date of Patent:** **** Mar. 11, 2025**

(54) **ELECTRONIC DEVICE WITH GRAPHICAL
USER INTERFACE**

(71) Applicant: **Apple Inc.**, Cupertino, CA (US)

(72) Inventors: **Marcos Alonso Ruiz**, San Francisco, CA (US); **Chanaka Karunamuni**, San Jose, CA (US)

(73) Assignee: **Apple Inc.**, Cupertino, CA (US)

(**) Term: **15 Years**

(21) Appl. No.: **29/844,161**

(22) Filed: **Jun. 27, 2022**

Related U.S. Application Data

(63) Continuation of application No. 29/756,996, filed on Nov. 2, 2020, now Pat. No. Des. 956,088, which is a continuation of application No. 29/707,721, filed on Sep. 30, 2019, now Pat. No. Des. 900,833, which is a continuation of application No. 29/617,024, filed on Sep. 11, 2017, now Pat. No. Des. 861,704.

(57) CLAIM

The ornamental design for an electronic device with graphical user interface as shown and described.

DESCRIPTION

The FIGURE is a front view of an electronic device with graphical user interface showing the claimed design. The outer broken lines in the FIGURE showing an electronic device form no part of the claimed design. The other broken lines in the FIGURE show portions of the graphical user interface that form no part of the claimed design.
